PICKUP TRUCK BED SUPPORTED TRAIL BIKE TRANSPORTER

Irving Dumm III, 8297 Oak Knoll Drive,
Roseville, Calif. 95678

Filed Sept. 29, 1970, Ser. No. 25,246

Term of patent 14 years

Int. Cl. D12—16

U.S. Cl. D14—6

Fig. 1

Fig. 2

Fig. 3

Fig. 4

Fig. 5

FIG. 1 is a perspective view of a pickup truck bed supported trail bike transporter, showing my new design; FIG. 2 is a front elevational view;

FIG. 3 is a top plan view;

FIG. 4 is a side elevational view, the opposite side being substantially similar in appearance; and,

FIG. 5 is a fragmentary sectional view to an enlarged scale emphasizing the wedge shape of the wheel troughs, the plane of the section being indicated by the line 5-5 in FIG. 3.

I claim:

The ornamental design for a pickup truck bed supported trail bike transporter, as shown and described.
